(57) **CLAIM**

The ornamental design for a round point blade, as shown and described.

DESCRIPTION

FIG. 1 is an isometric view of the round point blade; FIG. 2 is a top view of the round point blade; FIG. 3 is a bottom view of the round point blade; FIG. 4 is a right view of the round point blade; FIG. 5 is a left view of the round point blade; FIG. 6 is a front view of the round point blade; and, FIG. 7 is a back view of the round point blade. The broken lines in the drawings depict environmental subject matter only and form no part of the claimed design.
